US0D1017201S

(12) **United States Design Patent** (10) **Patent No.:** **US D1,017,201 S**
(45) **Date of Patent:** **** Mar. 12, 2024**

(54) **SHOE**

(71) Applicant: **STARLINK TECHNOLOGY CO., LIMITED**, Hongkong (CN)

(72) Inventor: **Jie Huang**, Singapore (SG)

(**) Term: **15 Years**

(21) Appl. No.: **29/883,838**

(22) Filed: **Feb. 3, 2023**

Related U.S. Application Data

(63) Continuation of application No. 29/810,962, filed on Oct. 11, 2021, now Pat. No. Des. 980,593.

(57) **CLAIM**

The ornamental design for a shoe, as shown and described.

DESCRIPTION

FIG. 1 is a perspective view of a shoe showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The dash-dash broken lines in the drawings showing the interior, mid sole, toe upper and bottom of the shoe depict portions of the article and form no part of the claim.

The dash-dot-dash lines in the figures show boundaries forming no part of the claimed design.

1 Claim, 8 Drawing Sheets
